HYDROFORMING WITH HYDROCRACKING OF RECYCLE PARAFFINS

Charles E. Hemminger, Westfield, N.J., and Donald Dunwody Dunlop, Baton Rouge, La., assignors to Esso Research and Engineering Company, a corporation of Delaware

Application December 14, 1955, Serial No. 552,996

1 Claim. (Cl. 208—66)

The present invention relates to improvements in the hydroforming of naphthas. More particularly it relates to a process for obtaining improved yields of hydroformate of satisfactory octane number and volatility.

Hydroforming is defined as an operation in which a petroleum naphtha is contacted at elevated temperatures and pressures and in the presence of a recycled hydrogen-containing gas with a solid catalytic material under conditions such that there is no net consumption of hydrogen. Hydroforming processes are well known at this time and the basic operation of the hydroformer is no part of this invention, e.g. see Petroleum Processing, August 1955, pages 1170 through 1196.

Usually the normally liquid feed stock boils substantially within the range of from about 150° to 430° F. and more particularly 200° to 350° F. The light ends, i.e., the material boiling from about 0° to 200° F., are not subjected to this reaction, for the reason that the virgin naphtha light ends have a fairly good octane rating. The feed or charging stock to the hydroforming reactor can be a virgin naphtha, a cracked naphtha, a Fischer-Tropsch naphtha, a mixture of these, or the like.

Hydroforming operations are ordinarily carried out in the presence of hydrogen or hydrogen-rich recycle gas at temperatures of 750° to 1150° F., in the pressure range of about 50 to 1000 pounds per square inch, and in contact with hydroforming catalysts.

The chemical reactions involved in the hydroforming process include dehydrogenation of naphthenes to the corresponding aromatics, isomerization of straight chain paraffins to form branched chain paraffins, isomerization of cyclic compounds such as ethylcyclopentane to form methylcyclohexane, and some aromatization, dealkylation and hydrocracking of paraffins. In a hydroforming operation which is conducted efficiently it is possible with the use of a proper catalyst and proper conditions of operation to hydroform a virgin naphtha having an octane number of about 50 to a hydroformate having an octane number of from 95 to 98 and obtain yields of C₅+ hydrocarbons as high as 85%.

Platinum has come into ever increasing use in hydroforming because of the high activity of this catalyst for conversion of naphthenes to aromatics. This high production of aromatics results in a hydroformate having a volatility less than desired. A segregation of the hydroformate to include only the fraction in the satisfactory volatility, i.e., boiling point range, results in yield diminution.

This invention relates to a procedure for the production of high octane gasoline having increased volatility. The present invention comprises separating the C₈ and lower hydrocarbon fraction from the C₉ and higher fraction by distillation and feeding the higher boiling material to a hydrodealkylation unit where the side chains are cracked to produce C₇ and C₈ aromatics. These C₇ and C₈ aromatics can have unsaturated side chains and

all or a part, i.e., a portion, are recycled to a hydrofiner to saturate the side chains and thereby improve the lead susceptibility.

The hydrofining, reforming and hydrodealkylation steps 5 are conventional and are not claimed per se.

The C₈ and lower fraction contains paraffins, naphthenes and aromatics, whereas the C₉ and higher fraction contains predominantly, i.e., at least 70 wt. percent aromatics. The separation of the two fractions is easily accomplished by distillation as at atmospheric pressure, the C₈—fraction boils typically in the range of 230° to 290° F., whereas the C₉+ fraction boils typically in the range of 290° to 350° F.

This invention will be better understood by reference 15 to the following example and discussion of the flow diagram shown in the drawing.

In the drawing fresh feed at a temperature of 650° F. is fed through line 1 to catalytic hydrofiner 2, although 20 the fresh feed can bypass it. The feed is hydrofined at 650° F. over a fixed bed of cobalt molybdate on alumina catalyst. Other hydrofining catalysts can be employed. H₂S and recycle gas are taken off through line 3, after passing through a separating means. Hydrogen for the hydrofining enters hydrofiner 2 through lines 26 and 1.

25 The hydrofined product after separation from the H₂S and recycle gas is then sent through line 4 to furnace 5 where it is heated to a temperature of 925° F. along with recycle gas from line 25. The gaseous mixture is fed through line 6 to reactor 7. The naphtha is 30 hydroformed over a fixed bed platinum on alumina catalyst at 925° F. The total mixture is discharged through line 8 to furnace 9 where it is again heated to reaction temperatures, e.g. 925° F., and then discharged via line 10 to second stage hydroforming reactor 11. Several 35 stages of reactors can be employed. The hydroformate together with recycle gas is discharged through line 12 to distillation column 13.

In distillation column 13 the C₉ and higher fractions leave through line 17 and are thus separated from the C₈ and lighter fractions. Recycle gas is taken overhead through line 16 and the C₄'s through line 14, the C₅ to C₈'s through line 15 for blending.

The recycle gas from line 16 and C₉+ from line 17 45 are sent to hydrodealkylater 19. The temperature is brought up to 1000° F. and at a pressure of 500 p.s.i., the aromatics are cracked to C₇'s and C₈'s. Polymer bottoms from line 18 can be discharged from the system or sent to the hydrodealkylater.

The reaction mixture is sent through line 20 to distillation column 21. The recycle gas is sent through line 28, line 24, line 26, and line 1 to hydrofiner 2. The cracked aromatic fraction is also sent to the hydrofiner through lines 23 and 1. Tar is discharged through line 55 22.

50 The process of this invention is applicable to fixed or fluid bed hydroforming preferably with noble metal catalysts. Suitable catalysts thus include the noble metals such as platinum and palladium, group VI metal oxides, such as molybdenum oxide, chromium oxide or tungsten oxide, or mixtures thereof upon a carrier such as activated alumina, zinc aluminate spinel, or the like. The catalysts contain about 0.01 to 2.0 weight percent platinum, about 5 to 15 weight percent molybdenum oxide, or from about 10 to 40 weight percent chromium oxide upon a suitable carrier. If desired, minor amounts of stabilizers and promoters such as silica, calcium oxide, ceria or potassia can be included in the catalyst. The catalyst particles are, for the most part, between 200 and 400 mesh in size, or about 0-200 microns in diameter, with a major proportion between 20 and 80 microns in fluidized operation.

In order to explain the process more fully, the following conditions of operation of various components are set forth below and in the examples.

Conditions in hydroformers		
	Preferred Range	Broad Range
Inlet Temperature, ° F.....	900-950	875-975
Pressure, p.s.i.g.....	250-500	100-700
Cu. ft. of recycled gas fed/bbl. of oil.....	2,500-7,000	2,000-10,000
Concentration of H ₂ in recycle gas.....	60-90	50-95

Conditions in hydrodealkylation unit		
	Preferred Range	Broad Range
Temperature, ° F.....	1,050-1,150	1,000-1,200
Pressure, p.s.i.....	200-700	50-1,200
Cu. ft. of gas fed/bbl. of oil.....	300-1,000	100-2,000
Concentration of H ₂ in recycle gas.....	60-90	50-95
Vol. oil per hr./per vol. coil above 900° F.....	0.5-2.0	0.2-5.0

Conditions in hydrofiner		
	Preferred Range	Broad Range
Temperature, ° F.....	600-650	550-700
Pressure, p.s.i.g.....	200-300	100-500
Recycle gas rate, s.c.f./bbl.....	500-800	200-1,500
Space velocity, ft./sec.....	3-5	2-10

The advantages of the process of this invention are demonstrated in the following examples of low and high severity operations.

Columns I under each are figures for conventional hydroforming.

Columns IA include the additional step of distilling to obtain a product that meets volatility specifications.

Columns IB under each includes conventional hydroforming plus hydrodealkylation as taught in this invention.

The figures are as follows:

Case.....	Operation.....	Low Severity			High Severity			
		I Hydro-forming	IA Hydro-forming + Dist.	IB Hydro-forming + Dealky.	I Hydro-forming	IA Hydro-forming + Dist.	IB Hydro-forming + Dealky.	
RON.....	RON.....	86.6 88.6	78.5 65.4	86.2 81.2	98.9 80.7	96.6 86.3	98.5 76.9	
Product Composition, Vol. Percent								
Fraction	Boiling Range, ° F.	C ₅	C ₆	C ₇	C ₈	C ₉	C ₁₀	
		80-98	2.2	3.0	2.4	7.2	10.3	7.7
		98-176	2.5	3.4	2.7	4.2	6.0	4.5
		176-231	29.9	40.5	52.1	28.4	40.7	55.8
		231-292	39.3	53.1	42.8	30.0	43.0	32.0
		292-349	20.7	—	—	22.4	—	—
		C ₁₀	5.4	—	—	7.8	—	—

 2,780,661 Hemminger et al. Feb. 5, 1957

These results show:

(1) Hydroforming alone (I) gives a product of insufficient volatility, i.e., does not meet the requirement of about 90 vol. percent boiling at 302° F.

(2) Straight distillation of the hydroformate (IA) results in a large loss in yield and octane number. The loss of the high boiling aromatics contributes to this.

(3) The process of this invention (IB) gives only a slight diminution in octane number over (I) but a marked increase in yield meeting volatility specifications, e.g., 81.2 vol. percent versus 65.4 vol. percent for low severity operations and 75.9 vol. percent versus 56.3 vol. percent for high severity operations.

It is to be understood that this invention is not limited to the specific examples, which have been offered merely as illustrations, and that modifications may be made without departing from the spirit of this invention.

What is claimed is:

A combination process wherein a naphtha feed stock containing both naphthenes and aliphatic hydrocarbons is first contacted with hydrofining catalyst and hydrogen under hydrofining conditions in order to remove sulfur, thereafter the hydrofining feed stock is contacted with a platinum hydroforming catalyst in the presence of hydrogen in a plurality of stages maintained under hydroforming conditions, thereafter the product obtained by hydroforming is subjected to a first distillation stage wherein the C₅ to C₈ hydrocarbons are recovered for gasoline blending purposes and the C₉'s and higher hydrocarbons are delivered to a hydrodealkylation stage maintained under hydrodealkylation conditions where the C₉'s and higher hydrocarbons are converted to C₇ and C₈ aromatic hydrocarbons, thereafter the product of hydrodealkylation is subjected to a second distillation step to remove tar bottoms and the C₇ and C₈ hydrocarbons are recycled to the fresh feed inlet where olefins present are hydrogenated, the result of the process being the formation of a gasoline blending stock which has a volatility such that about 90 volume percent boils at 302° F. due to the presence of a large preponderance of C₇ and C₈ aromatic hydrocarbons, possessing a high octane number and also possessing improved lead susceptibility.
